Primary Examiner — Rhea Shields

(57) **CLAIM**

The ornamental design for a combined periodontal sulcus brush and intrasulcular medicament applicator, as shown and described.

DESCRIPTION

FIG. 1 is a top, right side, and front perspective view of a first embodiment of a combined periodontal sulcus brush and intrasulcular medicament applicator, showing my design;

FIG. 2 is a right side elevation view thereof;
FIG. 3 is a left side elevation view thereof;
FIG. 4 is a front elevation view thereof;
FIG. 5 is a rear elevation view thereof;
FIG. 6 is a top plan view thereof; and
FIG. 7 is a bottom plan view thereof;
FIG. 8 is a top, right side, and front perspective view of a second embodiment of a combined periodontal sulcus brush and intrasulcular medicament applicator, showing my design;

FIG. 9 is a right side elevation view thereof;

FIG. 10 is a left side elevation view thereof;

FIG. 11 is a front elevation view thereof;

FIG. 12 is a rear elevation view thereof;

FIG. 13 is a top plan view thereof; and

FIG. 14 is a bottom plan view thereof; and

FIG. 15 is a top, right side, and front perspective view of a third embodiment of a combined periodontal sulcus brush and intrasulcular medicament applicator, showing my design;

FIG. 16 is a right side elevation view thereof;

FIG. 17 is a left side elevation view thereof;

FIG. 18 is a front elevation view thereof;

FIG. 19 is a rear elevation view thereof;

FIG. 20 is a top plan view thereof; and

FIG. 21 is a bottom plan view thereof; and

FIG. 22 is a top, right side, and front perspective view of a fourth embodiment of a combined periodontal sulcus brush and intrasulcular medicament applicator, showing my design;

FIG. 23 is a right side elevation view thereof;

FIG. 24 is a left side elevation view thereof;

FIG. 25 is a front elevation view thereof;

FIG. 26 is a rear elevation view thereof;

FIG. 27 is a top plan view thereof; and,

FIG. 28 is a bottom plan view thereof.

In the drawings, the broken lines are for the purpose of illustrating portions of the combined periodontal sulcus brush and intrasulcular medicament applicator that forms no part of the claimed design.
